US00D814520S

(12) **United States Design Patent** (10) Patent No.: **US D814,520 S**
 Martin et al. (45) Date of Patent: ** Apr. 3, 2018

(54) **DISPLAY SCREEN WITH GUI MENU FOR A MULTIFUNCTION OFFICE MACHINE**

(71) Applicant: **XEROX CORPORATION**, Norwalk, CT (US)

(72) Inventors: **Andrew T Martin**, Honeoye Falls, NY (US); **Robert Grasso**, Victor, NY (US); **Ken Hayward**, Brockport, NY (US)

(73) Assignee: **Xerox Corporation**, Norwalk, CT (US)

(**) Term: **15 Years**

(21) Appl. No.: **29/622,744**

(22) Filed: **Oct. 19, 2017**

(57) **CLAIM**

The ornamental design for a display screen with GUI menu for a multifunction office machine, as shown and described.

DESCRIPTION

FIG. 1 is a front view of a display screen with GUI menu for a multifunction office machine showing the new design; FIG. 2 is a front view of a display screen with GUI menu for a multifunction office machine showing a second embodiment of the new design; and,

FIG. 3 is a front view of a display screen with GUI menu for a multifunction office machine showing a third embodiment of the new design.

The outermost dot-dash broken lines illustrate an electronic device, the dot-dash broken line at the periphery of the figures illustrate the display screen, and the broken line showing of text illustrates portions of the GUI menu. None of the broken lines form part of the claimed design.

1 Claim, 3 Drawing Sheets
